ESCUTCHEON PLATE OR THE LIKE

Morris Falk, Leominster, Mass., assignor to Independent Lock Company, Fitchburg, Mass., a corporation of Massachusetts

Application March 27, 1937, Serial No. 133,371

7 Claims. (Cl. 70—452)

This invention relates to escutcheon plates; more particularly to escutcheon plates for doors.

The invention has for its objective the provision of escutcheon plates for doors which are of simple and inexpensive manufacture, and include constructional details whereby builder's hardware, of the character described, may have imparted thereto pleasing surface ornamentation, more particularly, contrasting color schemes, without the unusual expense involved for such purposes, such as may be entailed in the expense of complex coatings or in enamelling such parts as are employed to impart ornamental, as well as utilitarian features.

15 Where it has been found desirable to supply a demand for highly ornamental builder's hardware, particularly escutcheons carrying out predetermined surface finishing designs or color contrasts, in keeping with some general decorative plan, the provision of such hardware as escutcheons in a variety of embellished effects or colors, such as multi-tone or two-tone effects, required that such parts be more or less "custom made" as otherwise dealers in such products are not 20 prone to carry a large supply of a variety of decorated parts or of a variety of colored, or contrastingly colored parts, for fear that the whims of the trade for different ornamentation or contrasting color effects may leave the dealer with 25 a quantity of unsaleable or difficultly saleable products.

Accordingly, it is an object of my invention to provide an escutcheon plate permitting the employment of a variety of ornamental materials, such as bronze, plated materials, synthetic plastics ornamented in various colors, and to include in the construction of an escutcheon plate of this character, a separable element whereby different ornamental color effects may be produced. 30 It is contemplated by my invention to include in an escutcheon plate, simple and inexpensive mounting means for a replaceable or interchangeable element of exceedingly low cost, whereby this low cost element may be retained in stock 35 by the dealer, with different ornamental effects or in a variety of colors, without entailing any considerable expense, whereby this replaceable element may be interchangeably positioned with a simple number of, or a small stock number of 40 ornated primary escutcheon plates.

Thus, it is a further object of my invention to provide a primary body constituting an escutcheon, which may be made and ornamented in a comparatively simple number of stock ornamental finishes and with which a contrasting, inter-

changeable element may be associated, the replaceable element being of such low cost and being so readily replaced that a dealer may retain on hand such elements in large number and with a variety of finishes or color effects, to supply all reasonable demands, but without involving himself in an unusually high investment to meet such contingencies.

Accordingly, it is an object of my invention to provide means for supplying the trade with a wide variety of ornamental escutcheons, yet effecting considerable economy without entailing the dealer in large investments to meet all the contingencies and requirements of the trade.

To attain these objects and such further objects as may appear herein or be hereinafter pointed out, I make reference to the accompanying drawing forming a part hereof, in which—

Figure 1 is a plan view of an escutcheon plate for a door;

Figure 2 is a perspective view of a replaceable element therefor;

Figure 3 is a section taken on the line 3—3 of Figure 1;

Figure 4 is a section taken on the line 4—4 of Figure 1;

Figure 5 is a plan view of another embodiment of my invention;

Figure 6 is a section taken on the line 6—6 of Figure 5;

Figure 7 is a section taken on the line 7—7 of Figure 6;

Figure 8 is a section taken along the line of Figure 4, with another embodiment.

Making reference to the drawing, I have illustrated an escutcheon plate 10, exemplifying the form of the escutcheon plate that usually is associated with a door. The contour of the escutcheon may be given various configurations of pleasing and ornamental character, and may be made from a variety of materials, such as molded materials employing synthetic plastics, such as phenol formaldehyde condensation products, polymerized vinyl compounds, plasticized cellulosic compounds such as cellulose acetate, all of which may be made by a molding, die casting or injection casting method.

The main body of the escutcheon plate may likewise be made of cast metal, such as bronze, brass, or metal stampings, in which a variety of finishes may be imparted thereto, such as by nickel plating or chromium plating, or by bronze finishing or enamelling.

The escutcheon plate 10 may be formed at its face 11 with any desired surface configuration,

and includes a recess or orifice 12, into which there is fixed, by crimping, a door knob boss 13, having outwardly flared shoulders 14. It will be understood that the door knob boss may be integrally formed with the main body of the escutcheon plate in the manner which will appear more clearly as this description proceeds.

The front face of the escutcheon is provided with a surface terminating recess or seat 15, preferably of such contour as will ornamenteally conform with the general contour of the escutcheon plate. The recess may extend for a substantial part of the entire escutcheon plate; preferably however, the recess adjacent the lowermost portion 16 encompasses the affixing orifice 17.

The recess or seat 15, at its upper end, preferably terminates adjacent an overhang 18, provided by the shoulder 14 of the door knob boss. The body of the escutcheon is otherwise formed with a key hole 19.

With an escutcheon plate having the face terminating recess or seat as described, there is then provided an insert element 20, shown in Figure 2. This element 20 has its profile 21 corresponding to the contour of the recess or seat 15. The lower edge 22 includes a screw orifice 23, adapted to align with the orifice 17 in the body of the escutcheon. A key hole 24 is positioned on the element 20 to align with the key hole 19 formed in the body of the escutcheon. The upper end 25 serves as a means for affixing the same in the recess or seat 15 and for this purpose is arranged to be received underneath the overhang 18 provided by the shoulders 14 of the door knob boss 13.

With an insert element thus provided, a highly ornamental contrasting color and design effect is readily produced, as will be apparent from an inspection of Figure 1, with the element 20 inserted within the recess or seat 15. This is accomplished by first inserting the end 25 underneath the overhang 18 and then dropping the body of the element 20 within the recess 15. In this position, an attaching element such as a screw or bolt may be passed through the aligned orifices 23 and 17, to affix the element and escutcheon plate in position upon the door surface adjacent the lock.

At the upper end of the escutcheon, another screw orifice 26 may be provided, to provide additional means to attach the escutcheon plate in position.

It will be understood that the insert element 20 may be made of metal, to which an ornamental finish may be given, such as by bronzing, enameelling, nickel-plating, chromium-plating, or the like. This insert element may likewise be of plastic material, cut, cast or molded from such material.

The character of the insert element 20 will readily be understood to be of such low cost as to permit a trader to maintain on hand a large variety of such elements, each ornamented or finished to produce a large variety of pleasing effects in contrast with the background of the main body escutcheon plate.

It will be understood that while it is preferred by me to have the thickness of the element 20 correspond to the depth of the recess 15, to provide a surface termination of the element 20 with the surface 11 of the escutcheon 10, only a portion of the element 20 need be so formed to be received within the recess.

Thus, it is sufficient that the insert element have a seat corresponding to the recess 15, with portions extending beyond and above the surface

11, to give a raised appearance whereby different ornamental effects may be produced. It will also be understood that the portion extending outside of the recess may be given various contours, thereby to further increase and vary the ornamental contrast which may be imparted to the combined elements comprising the body portion of the escutcheon and the insert element 20.

In Figures 6 and 7 I have illustrated another embodiment of my invention in which the escutcheon plate 10a is more particularly suitable where it is desired to employ a synthetic plastic. In this construction, the body portion 11a is molded or otherwise formed to provide an orifice 12a, terminating in a door knob boss 13a, having an outwardly flared shoulder 14a, adjacent the face side. On the face side 11, there is formed a face terminating recess or seat 15a, one end whereof extends towards the edge 16a and overlies an attaching orifice 17a. The opposite end merges beneath the collar 14a, providing an overhang 18a by the slot formed by the recess 15a, which terminates in the wall of the orifice 13a of the boss for the door knob.

For purposes of facilitating the formation of the overhang orifice 18a in the illustration shown, there is provided the core orifice 18b. It will be understood that where manufacturing procedure dictates that the overhang orifice or slot 18a be provided separate from the molding or casting operation, this may be accomplished by a routing operation, in which event the core orifice 18b may not appear in the escutcheon.

Additionally, the molding operation may provide a keyhole orifice 19a, located in position in accordance with the embodiment previously described.

In all other respects, by the inclusion of the attaching orifice 26a, the embodiment described in Figure 6 includes all of the features of construction heretofore referred to in connection with the embodiment illustrated in Figures 1, 3 and 4, and may have combined therewith the insert element 20, illustrated in Figure 2.

Figure 5, therefore, provides an escutcheon body which is interchangeable with the escutcheon body illustrated in Figures 1 and 3, for the retention therein of the insert element 20.

In Figure 8 I have shown a fragmentary section of another embodiment of my invention in which the variable element receiving recess may extend through to the back surface of the escutcheon plate. In this embodiment, the main body of the escutcheon plate 10b is provided with a surface terminating recess 15a, extending from the front surface to the rear surface, and includes an undercut shoulder 15b. Otherwise, the surface terminating recess 15a may correspond to the form and contour of the variable insert element 20, in accordance with some predetermined outline.

With an escutcheon plate which includes the surface terminating orifice 15a and the overhang shoulder 15b, there may be provided an insert element 20a, the upper portion whereof 21a corresponds to the narrow portion of the recess 15a and the lower portion 21b corresponds in contour to be received by the overhang 15b.

With the construction shown in Figure 8, the variable insert element is positioned through the rear face of the escutcheon plate until the insert element 20a has the portion 21a nested within the recess 15a, and the portion 21b, and is held by the shoulder 15b and is nested within the enlarged portion so provided.

In other respects, the construction of the escutcheon plate will be readily understood except that this embodiment requires the inclusion of attaching orifices formed solely in the body of the 5 escutcheon plate, which in turn will hold the insert element 28a in position.

It will be understood that while I have described and illustrated my invention as having particular utility in connection with escutcheon 10 plates for doors in that this element receives a major consideration in ornamenting and effecting some ornamental treatment, and further in that this part of the door receives a great deal of wear due to handling, requiring renovation, it 15 will be understood that in certain respects my invention has applicability in switch plates, lighting fixtures, such as wall brackets and door knockers.

In general, it will be observed that I have provided an escutcheon plate in which great economies are effected in that a simple number of body members may serve interchangeably to mount a large variety of the insert elements, and that this element being of low cost, will not involve 25 a dealer in a large investment to meet the contingencies arising by reason of the need for different ornamental effects, color contrasts, and surface finishings, in the builder's hardware referred to.

30 While I have illustrated my invention in the preferred form, it will be understood that the exemplification is not to be construed as limiting, but within the scope of the appended claims.

Having thus described my invention and illustrated its use, what I claim as new and desire to secure by Letters Patent is:

1. An escutcheon comprising, in combination, a body portion and an interchangeable surface replacement element, means formed on the exposed 40 face of said body portion serving as locating means to seat said element and as attaching means, and means on said element cooperating with said first means for interfitting said locating and attaching means whereby a variable surface assembly of the cooperating body portion and element is obtainable.

2. An escutcheon comprising, in combination, a body portion and an interchangeable surface replacement inlay element, said body portion 50 having formed therein a surface terminating recess, said element being formed to have a portion thereof fit within said recess and means formed on said body and inlay element, respectively, for detachably holding said element in position.

3. An escutcheon comprising, in combination, a body portion and an interchangeable inlay element, said body portion having formed therein a surface terminating recess adjacent the front 60 face thereof, attaching orifices for said body portion, a boss member, said element being formed to have a portion thereof fit within said recess and including a portion thereof formed to engage said boss member, a plurality of orifices in said body portion and inlay element, one of which is a keyhole orifice, the other of which is an attaching orifice, said keyhole and attaching orifices in

said body and inlay portion being in alignment when said inlay is seated within said recess.

4. An escutcheon comprising, in combination, a body portion and an inlay element, said portion having formed therein a surface terminating recess, a portion of said body being formed with an overhang adjacent one end of said recess and a plurality of orifices encompassed within the body portion and extending through said recess, said inlay element having a portion thereof formed to be received within said recess and to engage said overhang and including a plurality of orifices, one of which is a keyhole orifice arranged to be aligned with the keyhole orifice of the body portion, the other orifices serving as 15 attaching means for the escutcheon assembly and for holding the inlay element in the seated position.

5. An escutcheon comprising, in combination, a body portion and an interchangeable surface replacement element, said body portion including a door knob boss having formed thereon an overhang, a surface terminating seat formed in the body portion for the replaceable element, one end of said seat underlying said overhang, an attaching orifice passing through said body portion adjacent the opposite end of said seat, said element including a portion formed to be received by said overhang and including an orifice adapted to align with said orifice whereby a fastening element may be passed through said aligned orifices, holding said element in position upon said seat and affixing said escutcheon assembly in position.

6. An escutcheon comprising, in combination, a body portion and an interchangeable surface replacement element, a seat for said element formed in the face of said body portion, a boss extending from the face of said body portion and provided with an interlocking portion adjacent one end of said seat, said element including a portion formed to correspond to said seat and having on one end thereof a portion removably engageable with said interlocking portion of said body portion, and cooperating fastening means on said body portion and element, respectively, 45 adjacent the opposite end of said element and body portion in relation to said interlocking portion.

7. An escutcheon comprising, in combination, a body portion and an interchangeable, readily removable surface inlay element, said body portion having formed therein a door knob boss and a surface terminating recess in the front face of said body portion, a locking overhang formed in said boss adjacent one end of said recess, said body portion including an escutcheon assembly 55 attaching orifice disposed opposite to said boss, said element having a profile adapted to be received within said recess, one end whereof underlying said overhang, the other end including 60 an orifice in alignment with the orifice of said body portion whereby an attaching element may be passed through said orifices to hold said element in assembled position with the body portion and affix said escutcheon in position.

MORRIS FALK.
